UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

COUNTING MACHINE.

Application filed December 30, 1922. Serial No. 609,847.

To all whom it may concern:

Be it known that I, CURTIS HUSSEY VEEDER, a citizen of the United States, residing in Hartford, in the State of Connecticut, have invented certain new and useful Improvements in Counting Machines, of which the following is a specification, reference being had to the accompanying drawing, forming a part hereof.

10 This invention is concerned particularly with the devices for resetting to zero, after a succession of counting operations, those number wheels which have been moved in such counting operations. Resetting devices intended for this general purpose are shown in Letters Patent of the United States No. 649,522, May 15, 1900, and No. 1,385,408, July 26, 1921, said Letters Patent No. 649,522 describing particularly the devices whereby 20 all of the number wheels can be reset to zero with less than one revolution of the common resetting shaft, while said Letters Patent No. 1,385,408 disclose particularly certain improved devices for actuating the resetting shaft and for applying a brake or stopping device to the number wheels at the instant when they have reached the zero position, in the resetting operation, in order to prevent overthrow. In the Letters Patent 25 last mentioned the transmission of motion from the actuating shaft to the resetting shaft is effected through a form of planetary gearing, in which the rotation of the transmitting gears on their axes is effected 30 through the partial revolution of such gears about an external axis, while the brake or stopping device for the number wheels is actuated by a grooved cam which is secured to the resetting shaft and moves with it. 35 In the present case the transmission of motion from the actuating shaft to the resetting shaft is effected through a form of planetary gearing as explained in said Letters Patent, but the brake or stopping device 40 for the number wheels, instead of being actuated through the movement of the resetting shaft itself, as before, is actuated independently of the movement of the resetting shaft and by the movement of the actuating shaft, through devices to be described. The 45 improved construction is more satisfactory in operation and is easier to manufacture and assemble. With this general purpose in view the invention consists in the means whereby 50 the brake or stopping device is actuated

from the actuating shaft and in certain details of construction to be explained. In the accompanying drawing, in which the invention is illustrated—

Figure 1 is a view in central longitudinal section of a counting machine equipped with the present invention, the number wheels being shown in elevation.

Figures 2 and 3 are views in vertical transverse section on the planes indicated by the broken lines 2—2 and 3—3 respectively of Figure 1.

Figure 4 is a detail view partly in horizontal section on the plane indicated by the broken line 4—4 of Figure 3.

Figure 5 is a detail view in section on the plane indicated by the broken line 5—5 of Figure 2.

The numbering mechanism may be of any usual or suitable construction, the present invention not being directly concerned therewith. So far as the same is represented in the drawing, it may comprise a numbering shaft shown at *a* with an arm *a'* to be connected to the part, the movements of which are to be counted, a series of number wheels *a'* mounted upon a common axis, a pawl frame *a* connected to the shaft *a* and by which the number wheels are driven forward, and a resetting shaft *b* which rests at one end in the end of the shaft *a*, constitutes the common support for the number wheels *a'*, and is provided with means, as shown in said Letters Patent No. 649,522, by which, through the oscillation of the resetting shaft, those number wheels which have been moved in successive counting operations are reset to zero when the counting operation has been completed. All of the parts thus far referred to, including the devices actuated by the resetting shaft for setting the number wheels to zero, may be of any usual or suitable construction, the present invention being concerned more particularly with the means for stopping the number wheels at the instant when they have reached the zero position, in the resetting operation, in order to prevent overthrow, and with certain of the supporting means to be described.

The end wall *c'* of the casing *c* is provided with a hub *c* to form a bearing for the actuating shaft *d* which has secured to it a suitable arm or finger piece *d'*, for operation by the finger. The actuating shaft *d*

has within the casing a flange d^2 provided with diametrically opposite studs d^3 on which are mounted planetary gears f which mesh internally with a pinion b' formed on resetting shaft b , the reduced end of such resetting shaft having a bearing in the inner end of the actuating shaft d . In the construction shown, the gears f are formed, opposite the teeth which mesh with the pinion b' on the resetting shaft, with the teeth f^2 , for engagement with the internal teeth g^2 carried by a fixed plate g^3 which is secured to a plate g^4 mounted in the casing c . The flange or head d^2 of the actuating shaft d is formed as an arm which, in the oscillations of the shaft d , moves in a suitably formed opening g^5 in the plate g^4 , the gears f oscillating in the space between the fixed plates g^3 and g^4 . The shaft d is oscillated in one direction by the application of the finger to the arm d' and in the other direction by a spring such as that shown at d^4 . These transmitting devices are constructed and operate substantially as shown in said Letters Patent No. 1,385,408.

In the present instance there is provided improved end thrust bearing for the left hand end of the actuating shaft d . As shown, the head or end of the shaft d has a hub d^5 which is received in a bar e which is secured at its ends, as by welding or riveting, to the main supporting plate g^4 . In the construction shown in the Letters Patent last mentioned, the stationary gear plate g^3 was supported by round pins driven in drilled holes, which construction was somewhat difficult to assemble and expensive to manufacture although it worked satisfactorily. In the present instance, the fixed gear plate g^3 is formed with T-shaped ends g^6 which are received in T-shaped slots g^7 formed in arms g^8 of the plate g^4 . This construction makes the assembling of the two plates easy while providing for the secure retention of the gear plate in position.

Passing now to the devices for stopping the number wheels at the instant when they have reached the zero position, in the resetting operating, it will be seen that one end portion of the cross arm or head d^2 of the actuating shaft is arranged to co-act with a forked arm h which is formed on or secured to the shaft i which carries the dogs i' for co-operation with the toothed driving wheels k^4 of the number wheels, the dogs i' , one of which is shown in broken lines in Figure 3, swinging into the path of the teeth of the driving wheel k as the number wheel reaches its zero position so as to prevent further movement of the driving wheel. The head d^2 of the actuating shaft and the forked arm h co-operate somewhat in the manner of a Geneva stop. The forked arm h has a finger h' which overlies and rests upon the head d^2 of the shaft d

when the latter is in its normal position of rest. Between the finger h' and the shaft i the arm h is recessed as at h^2 and below the recess is formed with a shorter finger h^3 . It will now be seen that when the shaft d is oscillated by the pressure of the finger, the head d^2 moves from contact with the finger h' of the arm h into the recess h^2 and against the shorter finger or shoulder h^3 , thereby oscillating the arm h and the shaft i upon the axis of the latter and so moving the dogs i' into the paths of the teeth of the driving wheels k and locking the number wheels against further movement.

The plate g^4 is provided at its upper end with a stop g^8 to limit the movement of the stop arm h .

It will be seen that the devices by which the movement of the number wheels is checked are simple in construction, easy to assemble, and direct and certain in operation. It will be understood, of course, that various changes in details of construction and arrangement can be made to suit different conditions of use and that the invention, except as pointed out in the accompanying claims, is not limited to the particular construction shown and described herein.

I claim as my invention:

1. In a numbering machine, the combination of number wheels, a resetting shaft, an actuating shaft therefor, having at its inner end a hub, a plate fixed in the casing, and a bar secured to the casing and having an opening to receive and furnish a bearing for the hub of the actuating shaft.

2. In a numbering machine, the combination of number wheels, a resetting shaft having a driving gear, an actuating shaft, a planetary transmitting gear carried by the actuating shaft and meshing with the gear of the resetting shaft, a plate fixed in the casing and having inwardly extended arms with T-shaped slots in the ends thereof, and a plate having teeth for engagement with the transmitting gear and having T-shaped ends for engagement with said T-shaped slots.

3. In a numbering machine, the combination of a number wheel, a resetting shaft, an actuating shaft, and intermediate devices whereby the resetting shaft is actuated therefrom, a dog for engagement with the driving wheel to prevent rotation thereof, and operative connections between the actuating shaft and the dog, independent of the resetting shaft, whereby the dog is moved into operative position by movement of the actuating shaft.

4. In a numbering machine, the combination of a number wheel, a resetting shaft, an actuating shaft having a head, operative connections between the actuating shaft and the resetting shaft, a stop shaft having a

dog for engagement with the number wheel to prevent rotation thereof, and a Geneva stop arm carried by said last named shaft, in operative relation with the head of the 5 actuating shaft.

5. In a numbering machine, the combination of a number wheel, a resetting shaft, an actuating shaft having a head, operative connections between the actuating shaft and 10 the resetting shaft, a stop shaft having a

dog for engagement with the number wheel to prevent rotation thereof, and a forked arm carried by said last named shaft and having a long finger to overlie the head of the actuating shaft, and a short finger for 15 contact with the head of the actuating shaft as the latter is oscillated.

This specification signed this 20th day of December A. D. 1922.

CURTIS HUSSEY VEEDER.
